UNITED STATES PATENT OFFICE.

NICHOLAS C. LEIDGEN, OF DETROIT, MICHIGAN.

SASH RAISING AND LOWERING DEVICE.

Application filed August 10, 1922. Serial No. 580,894.

To all whom it may concern:

Be it known that I, NICHOLAS C. LEIDGEN, a citizen of the United States of America, residing at Detroit, in the county of Wayne and State of Michigan, have invented certain new and useful Improvements in Sash Raising and Lowering Devices, of which the following is a specification, reference being had therein to the accompanying drawings.

10 This invention relates to a sash raising and lowering device and has special reference to a mechanism which may be readily mounted in the door frame or body walls of an automobile for regulating a sash in the 15 door or automobile body, and after the mechanism is understood, it will be apparent that the same can be generally used for raising and lowering members relative to a well or comparatively small compartments 20 in which the members are housed when in lowered positions.

One of the objects of my invention is to provide a raising and lowering device embodying a reciprocable member having 25 power imparted thereto from a rotary manually operated shaft, and these elements may be easily mounted in the well of a door frame for shifting a sash in and out of the well, the sash having a traveler engaging 30 the reciprocable member which is adapted to raise and lower the sash in suitable guides provided therefor in the well of the door frame.

Another object of this invention is to provide a reciprocable mechanism for raising 35 and lowering a window sash, said mechanism including a reciprocable member movable in a vertical plane and actuated by an operating member shiftable in a horizontal 40 or lateral plane.

A further object of this invention is to provide a sash raising and lowering device embodying telescopic screw members and novel pieces of hardware which insure a 45 safe and positive adjustment of the sash without any danger of the sash accidentally lowering because of its weight, and vibrations to which it may be subjected, particularly during the operation of an automobile 50 equipped with sash adjusting devices in accordance with my invention.

The above are a few of the objects attained by the construction to be hereinafter described, and reference will now be had to 55 the drawings, wherein

Figure 1 is a view in elevation of the

inner side of an automobile door frame having a sash and a device for raising and lowering the sash;

Fig. 2 is a vertical sectional view of the 60 same;

Fig. 3 is an enlarged horizontal sectional view of the door frame, sash and raising and lowering device;

Fig. 4 is an enlarged horizontal sectional 65 view of the device;

Fig. 5 is an enlarged vertical sectional view of a portion of the reciprocable member;

Fig. 6 is an enlarged vertical sectional 70 view of a portion of the device, illustrating a reciprocable operating member;

Fig. 7 is a horizontal sectional view of a door frame having a sash and a device operable by a reciprocable operating member, 75 and

Fig. 8 is an enlarged side elevation of the 80 another form of sash raising and lowering device embodying telescopic screw members.

In the drawing, the reference numeral 1 denotes, by the way of an example, an automobile door frame having a lower outside panel 2, a sill 3, a well 4, channel guides 5, a sash 6, and a sill frame 7, said sill frame 85 being ordinarily closed by an inside lower stationary panel, which has not been illustrated for the sake of clearance in showing the sash regulating mechanism. The above recited elements are of a conventional 90 form at present used in the automobile industry, and reference will now be had to my mechanism located within the well 4 for raising and lowering the sash 6 in the channel guides 5.

The mechanism includes a vertical support having its lower end attached to the bottom of the frame 1 and its upper end attached to the sill frame 7. Adjacent the lower end of the support 8 is an angle bracket or bearing 9 for a rotatable shaft 10, said shaft being rectangular in cross section, except for its ends, so as to establish rotative continuity between said shaft and a reciprocable member 11 slidable on said shaft, said member having its outer wall provided with diamond threads or grooves 12.

The upper end of the shaft 10 has a bushing 13 journaled in a bearing 14 carried by the support 8, and on the upper end of the shaft is a beveled gear wheel 15

meshing with a similar gear wheel 16 on an operating shaft 17, suitably journaled in the sill member 7 or the upper end of the support 8. On the outer end of the operating shaft 17 is a crank or handle 18 and by rotating this crank or handle the shaft 10 may be revolved in a desired direction.

Mounted on the inner face of the support 8 is a stationary nut member 19 engaging the threaded reciprocable member 11 to cause said member to reciprocate when the shaft 10 is revolved. Engaging the opposite side of the reciprocable member 11 is a traveler nut 20 having apertured lugs 21 slidable on guide rods 22 supported by the bearings 9 and 14 at the sides of the reciprocable member 11. On the traveler nut 20 is a stud 23 and rotatable on said stud is a hollow roller 24 which has its open end provided with a peripheral flange 25, said roller extending into a slot 26 in the depending arm 27 of a channel binder strip 28 on the lower edge of the sash 6. Encircling the stud 23 within the hollow flange roller 24 is a coiled expansion spring 29 and the expansive force of this spring holds the flanged end of the roller 24 normally against the arm 27 and the edges of the sash 6 normally against the channel guides 5, thus preventing rattling of the sash and the pieces of hardware articulated therewith.

When the shaft 10 is rotated and a reciprocable movement imparted to the member 11 the traveler nut 20 will be caused to reciprocate faster than the member 11 and the sash 6 may be raised and lowered depending on the direction in which the shaft 10 is rotated by the rotary operating shaft 17. Instead of using this rotary operating shaft, I may use the mechanism shown in Figs. 6 and 7. Mounted on the upper end of the shaft 10 is a pinion 30 meshing with a reciprocable rack 31 guided in a slotted frame 32 mounted on the inner wall of the sill member 7 at a longitudinal slot 33 providing clearance for a handle 34 attached to the rack 31. By shifting the handle 34 movement may be imparted to the shaft 10 in a desired direction.

Reference will now be had to the other form of operating mechanism shown in Fig. 8. The support 8 in this instance has a short shaft 10 journaled in the upper end of the support and in the upper end of a spiral screw member 35 fixed in or on the angle bracket or bearing 9 of the support 8. In threaded engagement with the stationary screw member 35 is a nut 36 mounted in the lower end of a tubular telescopic spiral screw member 37 slidable on the shaft 10 and adapted to rotate therewith. In screw-threaded engagement with the telescopic screw member 37 is a nut 38 having a stud 39 supporting the sash 6 as previously de-

scribed. Either the rotary or reciprocable operating mechanism previously mentioned may be employed for rotating the shaft 10, to cause the screw member 37 to telescope the screw member 35 and the nut 38 to travel on the screw member 37.

From the foregoing it will be observed that the sash shifting mechanism is carried by a single support that may be easily mounted in the well 4 for raising or lowering the sash 6, and the nature of the mechanism precludes accidental shifting of the sash because of its weight or vibrations to which the mechanism may be subjected during the operation of a vehicle.

It is thought that the utility and operation of the two forms of my device will be apparent without further description, and while in the drawings there are illustrated the preferred embodiments of my invention, it is to be understood that the structural elements are susceptible to such changes, in size, shape and manner of assembling, as fall within the scope of the appended claims.

What I claim is:—

1. Means for raising and lowering a sash comprising a support, a rotary shaft carried by said support and adapted to have rotation normally imparted thereto, a reciprocable member on said shaft, a stationary nut carried by said support and engaging said reciprocable member to cause it to reciprocate during rotation of said shaft, and a traveler nut engaging said reciprocable member and adapted to raise or lower the sash, said traveler nut being guided adjacent said support.
2. Means for raising and lowering a sash, as called for in claim 1, wherein the relation of said reciprocable member and said travel nut is such that said traveler is caused to travel faster than said reciprocable member.
3. Means for raising and lowering a sash, as called for in claim 1, and a spring pressed sash engaging roller carried by said traveler nut and adapted to prevent rattling of the sash.
4. Sash raising and lowering means comprising a reciprocable member, rotary means axially of said reciprocable member for imparting movement thereto, a traveler nut engaging said reciprocable member and the sash, and means engaging said reciprocable member to cause said member to reciprocate when actuated by said rotary means.

5. Sash raising and lowering means as called for in claim 4, wherein the last mentioned means engaging said reciprocable member is coaxially thereof.

6. Sash raising and lowering means comprising a support, guide rods carried thereby, a traveler nut slidable on said rods and adapted to shift the sash, a reciprocable member engaging said nut to impart move-

ment thereto, and means engaging said reciprocable member for reciprocating said member.

7. Sash raising and lowering means as called for in claim 6, wherein the last mentioned means includes a stationary nut and a rotary shaft.

8. Sash raising and lowering means as called for in claim 6, wherein the last mentioned means includes a manually driven

shaft axially of said reciprocable member, and a nut engaging the outer wall of said reciprocable member.

In testimony whereof I affix my signature in presence of two witnesses.

NICHOLAS C. LEIDGEN.
